UNITED STATES PATENT OFFICE.

RALPH R. JANES, OF BROOKLYN, NEW YORK, ASSIGNOR TO STANDARD KNITTING MILLS COMPANY, A CORPORATION OF NEW YORK.

CLOSED-CROTCH UNDERWEAR.

1,226,773.

Specification of Letters Patent. Patented May 22, 1917.

Application filed November 8, 1913. Serial No. 799,860.

To all whom it may concern:

Be it known that I, RALPH R. JANES, a citizen of the United States, residing in Brooklyn, in the city and State of New York, have invented certain new and useful Improvements in Closed-Crotch Underwear, of which the following is a full, clear, and complete disclosure.

My invention relates to men's union suit underwear and particularly to an arrangement for opening and closing the seat or crotch of such underwear. The object of my invention is to produce a closed crotch union suit which will be comfortable to the wearer, which will be easy to make and which can be made at a low cost with a minimum waste of material. A further object is to so combine the several pieces of cloth entering into the garment that the lines to be sewed will be substantially straight, thereby making the sewing operation easy and cheapening the cost of production. A still further object is to so arrange the parts that there will be no unnecessary cloth in the rear of the garment and no bunching of cloth between the wearer's legs. Other objects and advantages will appear from a description of the preferred embodiment of my invention shown in the drawing accompanying and forming a part 30 of this specification. In this drawing Figure 1 shows a rear view of my improved garment. Fig. 2 shows the way in which the material is cut to form the gussets used in the garment, shown in Fig. 1. Referring in detail to the drawing, the numeral 1 designates the body portion of the union suit, 2 the arm holes and 3 the legs. The garment is preferably formed out of a single tubular knitted member which is cut open in the back up to the point 4, located when in use at or near the middle of the back of the wearer. The tubular member is also cut in front from the yoke 18 to the lower extremity and a row of buttons 5 extending from the neck opening down to the crotch and are provided to close the front opening. The legs are formed by sewing together the adjacent edges 6 of the material as shown in Fig. 1. In order to close the seat and crotch of the garment I provide a large gusset member 7 (see Fig. 2) and a small triangular shaped gusset member 13. These are so shaped that two of each may be cut from a rectangular piece of material and as they need little or no finishing prior to being positioned in the

garment there is little or no loss of material. The large gusset member has five sides, viz., a straight side 8, two sides 21, 21' at right angles thereto, and two sides 22, 25 of unequal length forming angles greater than ninety degrees with the two sides 21, 21', and with each other. The straight edge of the large gusset member is secured to the edge 9 of the material at the rear of the garment from the point 4 down to the beginning of the leg seam at the point 10. The lower end of the gusset member 7 is folded back under the crotch and the straight edge 21 is then secured to the edge 11 of the material at the front of the garment. The edge 22 of the gusset member extends from at or about the point 23 to the button 24. The straight edge 25 extends from this button upwardly to the point 26. The free side of the gusset member 7 forms a flap 12 which extends over and substantially closes the crotch or seat opening. The small gusset 13 is inserted in the inner seam of the leg opposite the one to which the large gusset is secured, that is, the seam of the leg is left open above the point 10^a and edges 14 and 15 of the small gusset are sewed to the free edges forming the leg so that the edge 16 of the small gusset bulges out and overlaps the material of the large gusset, thereby effectively closing the seat or crotch. It will be seen from the foregoing that the small gusset is located substantially below the crotch and that there is only one flap in the finished garment, namely: that designated by the numeral 12, and formed as an integral part of the gusset 7. I have found that garments made in this manner with a single flap are more comfortable than those made with two flaps, since there is less tendency or likelihood of the goods in the former bunching and annoying the wearer. I have also discovered that by forming the gusset members 7 and 13, one large and carrying a flap and the other small and serving only as a gusset, that the lines to be sewed may be made substantially straight and the material may be cut as shown in Fig. 2, so as to avoid the scrapping and wasting of the material.

While I have described only one embodiment of my invention I am aware that modifications may be made by those skilled in the art without departing from the scope of my claims. What I claim is:

1. A garment of the kind described

formed of a tubular member severed in the front on a straight line from the top to the bottom and in the rear from the bottom to about the waist, the lower ends of the severed edges being sewed together thus forming the legs, while the outer edges of the tubular member are left unsevered, the severed portions of the tube at the back of the garment forming a posterior opening extending from the points where the edges are sewed together to form the legs to a point substantially at the waist of the garment, and a gusset inserted in one of said leg seams extending over and covering the aforesaid posterior opening.

2. A garment of the kind described formed of a tubular member severed on a straight line at the front and rear at about the vertical center of the tube to form two separate members on opposite sides of said central line, the front being severed from the top to the bottom and the rear from the bottom to about the waist, the lower severed edges of each of said two separate members being sewed together to form leg portions, the severed portions at the back of the garment being free from each other from the point where the legs are sewed together to a point at substantially the waist of the garment thereby forming a posterior opening, and a gusset sewed to one of the leg seams independent of the other leg seam and extending a short

distance below the crotch and having its free portion sewed to the opposite edge of 35 the same leg member, said gusset forming a flap which extends over said posterior opening.

3. A garment of the kind described, formed of a tubular member, the front wall 40 of which is cut on a centrally disposed vertical line extending from the yoke to the lower end of the tubular member and the rear wall of which is severed on a centrally disposed vertical line extending from the 45 lower end of the garment to a point located a substantial distance above the crotch of the finished garment, legs formed by joining the edges of the front and rear walls of the tube, a main gusset and seat 50 closure piece extending down the back of the garment and looped around the crotch, said gusset member comprising a flap adapted to substantially close the seat or rear opening, and a relatively small gusset 55 member substantially triangular in shape located in the seam of one leg substantially below the crotch and adapted to coöperate with the main gusset member and complete the closure of the crotch, substantially as 60 described.

RALPH R. JANES.
